UNITED STATES PATENT OFFICE.

GEORGE W. COPELAND, OF MALDEN, AND MATTHIAS BROCK AND JOSEPH E. CRISP, BOTH OF BOSTON, MASSACHUSETTS; SAID BROCK AND CRISP ASSIGNORS TO SAID COPELAND.

LASTING-MACHINE.

SPECIFICATION forming part of Letters Patent No. 244,714, dated July 19, 1881.

Application filed June 21, 1881. (Model.)

To all whom it may concern:

Be it known that we, GEORGE W. COPELAND, of Malden, MATTHIAS BROCK, of Boston, and JOSEPH E. CRISP, of Boston, all in the State 5 of Massachusetts, citizens of the United States, have invented a certain new and useful Improvement in Boot and Shoe Lasting Machines, of which the following is a full, clear, and exact description, reference being had to 10 the accompanying drawings, forming a part of this specification, in explaining its nature, in which—

Figure 1 is a vertical section of the machine. Fig. 2 is a plan thereof. Fig. 3 is a detail view, 15 enlarged, representing a portion of the machine hereinafter referred to. Fig. 4 is a plan, enlarged, of a portion of the mechanism below the line $\alpha\alpha$ of Fig. 1.

This invention relates more especially to devices for lasting the toe and heel portions of 20 boots and shoes, and it embraces, first, means for holding the upper to the side of the last, about the toe or heel, prior to the folding of the edge thereof upon the surface of the in- 25 sole; second, folding-plates, or devices for fold- ing the edge of the upper upon the insole, and a gang or group of devices for driving fasten- 30 ings simultaneously or by a single impulse after the folding-plates have performed their 35 functions, and which may or may not be placed in position to be operated by them; third, the construction and arrangement of parts here-inafter more fully described.

In the drawings, A is the last. It is mounted 35 at the heel upon the pin a of the jack A', and at the toe upon the toe-support a' of the jack. The pin and toe support of the jack project upwardly from the bed a^2 , which is pivoted, so as to be revolved, at a^3 to the sliding plate a^4 . 40 This sliding plate has a horizontal movement, in suitable guides, to and from the lasting de- vices.

The appliance or device for holding the edge 45 of the upper against the side and end surface of the last consists in two curved arms, B B', each of which is shaped and conformed to that portion of the side and end of the last upon which it is to operate. They may be made of steel, sufficiently thin to conform by yielding

to the surface of the last; or they may be made 50 of metal, and be lined upon their surfaces with rubber or leather or other material; or they may be made in any other suitable way. They are each mounted on a yielding or spring arm, b, and one is arranged to project slightly in 55 advance of the other, so that upon the presentation of the last and upper thereto they shall be brought in contact with the holding device upon one side and corner, and the upper drawn up by pinchers, or in any other suitable way, upon that side and corner immedi- 60 ately before being brought in contact, and while being brought in contact, with said advance holding device; and that portion of the upper having been drawn up and fitted and 65 being held by the holding device, the last and upper are then moved to the other upper-holding device, adapted to act upon the other cor- 70 ner and side of the last, and the upper is pulled up by pinchers, or any other way, imme- 75 diately before and while being brought in contact therewith, and is held up thereby after- 80 ward until the action of the folding-plates; or, in other words, the two upper holding or clamping devices are so arranged in relation 85 to each other and to the jack that that portion of the upper about one corner of the last is first fitted to the end and side surface of the last, and held up by the holding-plate; and that then the portion about the other corner 90 is brought in contact with the second or other upper-holding device and fitted to the last, as explained, whereby the toe or heel of the upper is fitted to the toe or heel end of the last in successive sections. Of course these up- 95 per-holding devices may be secured to a moving block or head, as herein described; or they may be stationary, and the last moved in relation thereto; or the last may be stationary and they may be moved in relation to it with- out departing from the spirit of this portion of our invention.

The next feature of our invention has to do with the folding of the edge of the upper upon the insole at the toe and heel, and the fasten- 95 ing of the edge thus folded to the insole by a group or gang of fastenings driven by a single impulse or simultaneously.

We have represented the jack as capable of being reversed or revolved on a horizontal plane, and we have represented the spring-arms carrying the upper-holders B B' as secured to the block or post b'. This block or post projects downwardly from the plate or bed C, which is adapted to slide horizontally in suitable ways, c, in the frame c' of the machine, and this frame c' is provided with the post c'', which enters the socket c''' on the standard c'', and furnishes means whereby the frame-bed and appendages may be revolved. One end of the sliding bed or plate carries the toe-lasting plates D D'. These plates are pivoted at their inner ends to the post d, and upon the inward movement of the bed or plate are caused to be shut or closed upon the surface of the insole by means of the rolls d'' d''' upon the frame c'. The outer surface of the plates coming in contact with the rolls as the bed or plate slides inwardly, causes the plates to be closed. The folding-plates are provided with a series of holes or nozzles, e, which are arranged a little back from the edge of the plates, and in these holes or nozzles a corresponding series or group of drivers, E, are arranged to be reciprocated by any suitable means; and we describe as one the attachment of the drivers to the hinged blocks e', and the use of the rod d, in connection with a treadle when operated by foot-power, and a cam or lever when operated by motive power, for reciprocating said blocks. In this event the blocks would be hinged upon the rod d, and would be provided a vertical movement.

The spring c'' may or may not be used for returning the blocks to their normal position in connection with the mechanism herein described for reciprocating them. Each drive-way, nozzle, or hole e has opening into it a feed-passage, e'', preferably horizontal, by which the fastenings are fed to the drivers.

The fastening we prefer to use is that shown and described in Letters Patent No. 197,609, granted said Copeland and Brock, and dated November 27, 1877, and No. 186,663, granted said Copeland.

The shape of feedway, the device for feeding said strip, and the manner of driving tacks therefrom are shown and described in Letters Patent No. 197,608, granted Copeland, Woodward and Brock, dated November 27, 1877; and in No. 234,854, granted said Copeland and Brock, dated November 30, 1880; and we need not, therefore, further describe the construction and operation of the fastening-driving mechanism, excepting to say that such devices, when used for driving fastenings in this invention, are arranged in gangs or groups, each device having a nozzle, feedway, feed mechanism, and driveway substantially like those described in said Letters Patent, the drivers, however, being arranged to be operated together, or by a single impulse, the feedways being converging, or substantially converging, in direction, and the nozzles preferably being

formed in the folding-plates, and being placed or moved into position in relation to the edge of the last by them.

In operation the upper, being mounted upon the last and secured thereto temporarily at the toe and heel, is, with the last, placed upon the jack, and the upper, last, and jack are then moved to the upper-holding device, and the upper having been fitted to the sides and ends, and being held by the holding device, the edge to be folded being above the surface of the insole and in a vertical position, the upper, last, jack, and upper-holding device are then moved horizontally under the folding-plates, and by their continued movement cause the folding-plates to be closed upon the surface of the insole, thereby folding the edge of the upper thereon, and at the same time bringing the group or gang of driving devices in proper position for driving the group or gang of fastenings. The group or gang of fastenings is then driven simultaneously or by a single impulse.

This description of the operation of the machine answers as well for the heel lasting and securing appliances as for the toe, and the toe having been lasted, the only thing necessary to do to last the heel is to reverse the jack and reverse the frame c', and the other end of the frame, which is provided with the heel-lasting appliances, which are in every respect, excepting that of shape, a counterpart of the lasting devices already described, are brought into the position occupied by the toe-lasting devices, and the heel is then lasted, as above described.

The heel-lasting devices, being secured at the end of the sliding plate C, are by the movement of the toe-lasting plates inwardly caused to assume, automatically, the proper position 105 which the apparatus should bear at the commencement of the lasting—that is, the upper-holding devices are thrown forward and the folding-plates are opened.

We have shown the springs f attached to the folding-plates and to the sliding plate for automatically opening the plates; but any other suitable equivalent device may be employed.

Of course we do not confine ourselves in the practice of this invention to the arrangement of the folding-plates and fastening-driving devices herein described, or to the use of fastening-driving devices adapted to drive only the "Copeland tack-strip," so called; but we may use, in combination with the folding-plates, any arrangement of devices for driving fastenings of any description desirable, and may give them any suitable location and movement in relation to the lasting-plates, the essential features being that the devices for driving fastenings shall be so constructed and located that they can be brought in position either by their movement in relation to the last or the movement of the last in relation to them, and the fastenings driven simultaneously, or by a single impulse, while the lasting-plates are

holding the turned-in edge upon the surface of the insole.

The advantages of this invention are that the toe and heel, or either, can be lasted much 5 more rapidly than by the ordinary toe and heel lasting mechanism.

In lieu of reciprocating the drivers, as herein described, we mention the use of a hammer, by which the blocks supporting the drivers may be driven downwardly against the stress of the spring e^2 .

Having thus fully described our invention, we claim and desire to secure by Letters Patent of the United States—

15 1. In a machine for lasting the uppers of boots and shoes, the upper-holding devices B B', one of which is arranged in advance of the other and adapted to operate or be operated upon before the other, all substantially as and 20 for the purposes described.

2. In a machine for lasting the uppers of boots and shoes, the combination of a jack for holding the last, having a horizontal movement, upper-holding devices adapted to be 25 brought in contact with the edge of the last at the toe or heel in successive order, and folding-plates for simultaneously folding the edge of the upper held up by the upper-holding devices upon the surface of the insole, all substantially as and for the purposes described.

3. The combination of the last, the jack having a horizontal movement in relation to the upper-holding devices, the upper-holding devices, one arranged in advance of the other, 35 and the lasting-plates secured to the bed, having a horizontal movement, whereby upon a movement of the last horizontally in one direction the upper is clamped to the edge of the

last at the toe or heel, and by the continued horizontal movement in the same direction its 40 edge is folded upon the surface of the insole, all substantially as and for the purposes described.

4. In a machine for lasting the uppers of boots and shoes, the combination of the last, 45 a jack for supporting it, the toe or heel folding plates, and a gang or group of fastening-driving devices supported and adapted to be positioned by the movement of the lasting-plates, all substantially as and for the purposes 50 described.

5. In a lasting-machine for lasting the toes and heels of boots and shoes, a revolving jack having a horizontal movement, a last carried by said jack, and toe and heel lasting devices 55 arranged at opposite ends of a bed or table and adapted to be used successively, all substantially as and for the purposes described.

6. In a lasting-machine, toe and heel lasting devices arranged at opposite ends of a bed or 60 table and adapted to be used successively in lasting the toe and heel of a boot or shoe, all substantially as and for the purposes described.

7. In a lasting-machine, the combination of radially-converging folding-plates, a group of 65 nail-drivers carried by suitable arms or supports which are adapted by mechanism, substantially as described, to be moved to a position coincident with the plates, and tack or nail strip feeding mechanism, as set forth.
